UNITED STATES PATENT OFFICE.

VIOLA A. SMITH, OF NEW YORK, N. Y.

ADJUSTABLE BUST-CONFINING GARMENT.

1,406,692.

Specification of Letters Patent. Patented Feb. 14, 1922.

Application filed August 28, 1920. Serial No. 406,691.

To all whom it may concern:

Be it known that I, VIOLA A. SMITH, a citizen of the United States, and a resident of the city of New York, borough of Manhattan, in the county and State of New York, have invented a new and Improved Adjustable Bust-Confining Garment, of which the following is a full, clear, and exact description.

10 The invention relates to women's wearing apparel and its object is to provide a new and improved adjustable bust confining garment more especially designed for the use of stout, fleshy women, and arranged to distribute the flesh of the bust towards and under the arms and in a downward direction and away from the median line of the front thus giving a dressy appearance to the user. Another object is to draw the shoulder flesh 20 that protrudes over the upper edge of the back of the corset over the shoulders to the front and to evenly distribute it over the shoulders. Another object is to hold the bust firm and prevent the same from becoming 25 drooping and flabby. Another object is to enable the user to readily adjust the garment to produce the desired result.

With these and other objects in view, the invention consists of certain novel features 30 of construction as hereinafter shown and described and then specifically pointed out in the claims.

A practical embodiment of the invention is represented in the accompanying drawings 35 forming a part of this specification, in which similar characters of reference indicate corresponding parts in all the views.

Figure 1 is a front perspective view of the improved adjustable bust confining garment as applied;

Figure 2 is an enlarged cross section of the same on the line 2—2 of Figure 1;

Figure 3 is a view of the inner face of the divided back of the garment;

Figure 4 is a front perspective view of a modified form of the adjustable bust confining garment; and

Figure 5 is an enlarged cross section of the same on the line 5—5 of Figure 4.

50 The body 10 of the adjustable bust confining garment is approximately in the form of a sleeveless close fitting waist or corset cover, and the body 10 is of unbroken continuity and is adapted to be opened and closed at the back. For this purpose the ends of the body 10 are provided with suitable

fastening devices 11, such as hooks and eyes, for closing or opening the body at the back. The body 10 is formed of a number of sections fastened together and shaped to provide bust portions 12 terminating in inverted V-shaped or triangular shoulder portions 13 having their apexes extending to the shoulders of the wearer, as plainly indicated in Figures 1 and 4.

Shoulder straps 14 are attached to the back of the body 10 at opposite sides of the back median line, as plainly shown in Figure 3, and the front ends of the shoulder straps 14 are provided with loops 15 slidingly engaged by tightening straps 16 extending down over the bust portions 12 and passing through guide loops 17 attached exteriorly to the body 10 at the bust portions 12. The loops 15 are provided with inwardly projecting pins 75 34, which engage with perforations 33', grouped in pairs along the tightening straps adjacent to loops 15, and when so engaged hold the straps firmly in the desired position. The loops 15 are further provided with lugs 80 36 which keep the shoulder straps 14 and tightening straps 16 from becoming entangled. The lower ends of the tightening straps 16 are provided with rows of eyelets 85 18, of which any one of the eyelets of a strap is adapted to be engaged with a hook 19 secured to a shield 20, preferably of V-shape, and attached to the lower end of the body 10 at the front median line thereof. The apex of the shield 20 is provided with a 90 strap 21 carrying a loop 22 adapted to engage one of the studs 23 on the corset 24 worn by the user.

It will be noticed that the lower edge of the body 10 fits snugly around the waist 95 of the wearer and is held in this position by the connection of the shield 20 with the corset 24.

In order to don the garment, the tightening straps 16 are loosened in the loops 15 to 100 permit the user to readily pass the arms through the shoulder straps 14, after which the rear ends are closed by the fastening devices 11. When this has been done, the user pulls downward on the tightening straps 16 105 whereby the bust portions 12 are flattened out in a rearward direction thus drawing the flesh of the bust in a like direction, that is, towards and under the arms and away from the front median line. The flattening of the 110 bust portions 12 also tends to flatten the flesh of the bust in a downward direction thus

uniformly distributing the flesh of the bust at the front of the body in a rearward and downward direction. It will also be noticed that on drawing the straps 16 tight, a pull is exerted on the shoulder straps 14 to draw the back shoulder flesh which protrudes above the upper edge of the corset in a forward direction over the shoulders thus distributing such flesh at the shoulders and 10 eliminating the bulges at the back. After the straps 16 have been tightened they are fastened to the hooks 19 on the shield 20. It will be noticed that the tightening straps 16 allow of lowering the shoulder straps 14 and hence permit the back of the body 10 to drop down to the waist line to allow the user to readily engage the fastening devices 11 and thereby close the back without undue straining of the arms. After the back is 20 closed, the user exerts a downward pull on the tightening straps 16 to draw the back up into place, and on a further downward pull cause a flattening of the bust portions 12, as above described.

25 It will further be noticed that the shoulder straps 14 and the tightening straps 16 extend from the shoulders of the wearer downward and converge toward the median front line thus extending over the bust portions 12 at 30 the sides near the median front line and thereby tending to flatten the bust portions 12 and the bust rearward and downward as above mentioned.

In the modified form shown in Figures 4 35 and 5, each shoulder strap 30 is attached to the back of the body 10, the same as above described relative to the shoulder straps 14, but the shoulder straps 30 are made sufficiently long to slidably engage adjacent 40 buckles 31 fastened by short straps 32 to the shoulder portions 13 of the body 10, and the ends of the shoulder straps 30 are then passed through holding loops 33 attached to the body 10 above the bust portions 12. It 45 is understood that in this case the shoulder straps 30 are tightened by exerting a downward pull at the front end to draw the shoulder straps through the buckles 31 until the bust portions 12 are flattened out, the same 50 as above described in reference to the tightening straps. Otherwise the construction of

the garment is the same as the one above described and shown in Figures 1, 2, 3 and 4.

It is understood that the wearer can readily do the adjusting at the front while the garment is in place, closed at the back and held down by the shield 20 and its holding strap 21.

Having thus described my invention, I claim as new and desire to secure by Letters Patent:

1. As an article of manufacture, an adjustable bust confining garment, comprising a sleeveless close fitting waist of unbroken continuity and having bust portions, the waist being adapted to be opened and closed at the back, shoulder straps attached to the back and extending over the shoulders to the front, loops held on the front ends of the said shoulder straps, tightening straps attached to the front of the waist above the bust portions and slidably engaging the said loops to allow of drawing the straps tight and exerting a rearward pull on the said bust portions to flatten the latter and thereby distribute the flesh of the bust in a rearward direction, a shield at the front lower end of the said waist, and means connecting the lower ends of the said tightening straps to the said shield. 80

2. As an article of manufacture, an adjustable bust confining garment, comprising a sleeveless close fitting waist of unbroken continuity and having bust portions, the waist being adapted to be opened and closed at the back, shoulder straps attached to the back and extending over the shoulders to the front, loops held on the front ends of the said shoulder straps, tightening straps attached to the front of the waist above the bust portions and slidably engaging the said loops to allow of drawing the straps tight and exerting a rearward pull on the said bust portions to flatten the latter and thereby distribute the flesh of the bust in a rearward direction, a shield at the front lower end of the said waist, means connecting the lower ends of the said tightening straps to the said shield, and means on the shield to fasten the latter to another garment. 95

VIOLA A. SMITH.
